DESIGN FOR A TAX STAMP OR SIMILAR ARTICLE

Donald M. Turner, Providence, R. I.

Application June 24, 1938, Serial No. 78,015

Term of patent 3½ years

To all whom it may concern:

Be it known that I, Donald M. Turner, a citizen of the United States, residing in Providence, in the county of Providence, and in the State of Rhode Island, have invented a new, original, and ornamental Design for a Tax Stamp or Similar Article, of which the following is a specification, reference being had to the accompanying drawing, forming part thereof:

The single figure is a plan view of a stamp showing my new design enlarged on a scale of 2½ to 1.

I claim:

The ornamental design for a tax stamp or similar article, substantially as shown and described.

DONALD M. TURNER.
